[57] **CLAIM**

The ornamental design for a combination electronic telephone directory, telephone dialer and schedule organizer, as shown and described.

DESCRIPTION

FIG. 1 is a top perspective view of our new design for a combination electronic telephone directory, telephone dialer and schedule organizer, shown in the closed position for compact storage;

FIG. 2 is a top perspective view of the design shown in the open position, ready for use;

FIG. 3 is a front view of the design shown in the closed position;

FIG. 4 is a right side view of the design shown in the closed position, the left side view being a mirror image thereof;

FIG. 5 is a top plan view of the design shown in the closed position;

FIG. 6 is a bottom view of the design shown in the closed position;

FIG. 7 is a rear view of the design shown in the closed position; and,

FIG. 8 is a top plan view of the design shown in an open, flattened-down position.
